UNITED STATES PATENT OFFICE.

GEORGE S. GUY, OF PETERSBURG, VIRGINIA.

UMBRELLA NAME-AND-ADDRESS TAG.

SPECIFICATION forming part of Letters Patent No. 596,873, dated January 4, 1898.

Application filed March 25, 1897. Serial No. 629,228. (No model.)

To all whom it may concern:

Be it known that I, GEORGE S. GUY, a citizen of the United States, residing at Petersburg, in the county of Dinwiddie and State 5 of Virginia, have invented new and useful Improvements in Umbrella Name-and-Address Tags, of which the following is a specification.

The chief object of the present invention is to provide a novel, simple, efficient, economical, and easily-operated name-and-address tag particularly designed for attachment to the rib of an umbrella, but susceptible of general application or attachment to any article or object which it is desired to identify by providing the same with the name or name and address of the owner.

To accomplish this object my invention consists in the features of construction and in the combination or arrangement of parts hereinafter described and claimed, reference being made to the accompanying drawings, in which—

Figure 1 is a perspective view of the improved name-and-address tag, the scale being 25 about the full size of the device as actually manufactured. Fig. 2 is a detail perspective view, on a larger scale, of the longitudinally-slotted cylinder or tube. Fig. 3 is a detail perspective view of the rotary pin or rod having a finger-piece at one end carrying a device by which the tag can be attached to an umbrella-rib or other article. Fig. 4 is a detail perspective view of the flexible name or address sheet. Fig. 5 is a longitudinal sectional view showing the parts in position; and Fig. 6 is a transverse sectional view, on a larger scale, of the parts shown in Fig. 1.

In order to enable those skilled in the art to make and use my invention, I will now describe the same in detail, referring to the drawings, wherein—

The numeral 1 indicates a hollow cylinder or tube having a continuous slot 2 extending approximately the full length thereof. This 45 cylinder or tube is provided at its ends with inserted heads or plugs 3, having central bores or orifices 4, designed for the passage of the rotary pin or rod 5 in such manner that when the pin or rod is supported in position 50 it can be readily rotated in either direction through the medium of a finger-piece 6, rigidly secured to one end of the pin or rod. The

finger-piece 6 is preferably in the form of a disk having a milled or roughened periphery, but it may be of any construction suitable to 55 be manipulated by the fingers. The flexible name-and-address sheet 7 is of a width approximately coincident with the length of the longitudinal slot 2 and is preferably of parchment, which can be written upon with pen 60 and ink; but this sheet may be of any flexible fabric suitable for the purpose in hand—that is, a fabric which can be wound upon and unwound from the pin or rod 5 and be provided in any suitable manner with the name 65 or name and address of the owner of the umbrella, article, or object which is to be provided with the improved name-and-address tag. The flexible sheet 7 is secured at one end to the pin or rod 5 and is adapted to move 70 back and forth through the longitudinal slot 2. The outer end of the flexible sheet is provided with a bead or rib 8, which protects the edge of the sheet and also prevents the latter from being drawn entirely into the cylinder 75 or tube when the pin or rod is turned in the direction to wind up the sheet. I prefer to connect the inner end of the flexible sheet with the pin or rod by constructing the latter in the form of a slender tube having a longi- 80 tudinal slot 9, into which the inner end of the flexible sheet can be inserted and secured by pressing the edges of the slot upon the sheet. I do not, however, limit myself to this particular means of securing the inner end of the 85 flexible sheet to the pin or rod.

The improved device is designed to be secured to the rib of an umbrella or to any other article or object which is to be supplied with the name or name and address of the owner. 90 To accomplish this purpose, I provide the device with two clips 10, extending around opposite ends of the cylinder 1 and each composed of two arms or members 12, shaped to embrace the umbrella-rib 13 or any other article or object and having their extremities extended to form short shanks 14, which are screw-threaded and can be pressed together for the reception of a screw-nut 15 for the purpose of holding the arms or members 12 95 100 clamped upon the umbrella-rib 13 or other object. The clips 10 may be separate pieces brazed or otherwise secured to the cylinder, and they are placed upon the latter at the ends

thereof, so that they will not interfere with the movement of the flexible sheet when it is wound upon or unwound from the pin or rod 5.

The specific means shown for connecting 5 the cylinder or tube with the umbrella-rib or other article or object will in practice be found efficient and satisfactory; but while it is essential to provide suitable means for attaching 10 the device to or connecting it with an umbrella-rib or other article, I do not wish to be understood as confining myself to the use of the particular clips illustrated in the drawings, as any suitable form of clip may be used, and it may be connected with the cylinder or 15 tube other than as represented in the drawings.

The device can be very economically manufactured and placed on the market at a comparatively small cost, in that the cylinder or 20 tube is readily made of sheet-brass or other metal, the end heads or plugs are easily inserted and secured, and the pin or rod can be made by simply turning a strip of metal into the form of a tube, thus enabling the flexible 25 sheet to be connected therewith in a very simple manner.

Having thus described my invention, what I claim is—

1. A name-tag for an umbrella, or other object, consisting of a hollow cylinder having a longitudinal slot which extends to and opens 30 at one end thereof, heads fitted into the cylinder, a rotary pin journaled in the heads and having at one end an attached finger-piece, by

which it can be rotated in either direction, a 35 flexible name-sheet secured at one end to the pin and provided at its opposite end with a bead, and two clips rigidly secured, respectively, to the ends of the cylinder and each having screw-threaded shanks, and nuts engaging said shanks to connect them and retain the cylinder on the umbrella-rib, or other object, one of said clamps serving to close the open end of the longitudinal slot at one end of the cylinder, substantially as described. 40 45

2. A name-and-address tag for an umbrella, or other object, consisting of a cylinder constructed with a longitudinal slot, heads fitted in the ends of the slotted cylinder, a rotary pin journaled in said heads, a flexible name-sheet secured at one end to the pin and extending through the longitudinal slot in the cylinder, a finger-piece for turning the pin, or rod, and two clips encircling and secured to the opposite ends of the cylinder, and each 50 composed of two arms having their extremities extended into screw-threaded shanks, and a nut for engaging said shanks to clamp the said clips upon the rib of an umbrella, or other object, substantially as described. 55 60

In testimony whereof I have hereunto set my hand in presence of two subscribing witnesses:

GEORGE S. GUY.
